UNITED STATES PATENT OFFICE.

HOWARD M. DUDLEY, OF PHILADELPHIA, PENNSYLVANIA.

APPARATUS FOR DYEING OR OTHERWISE TREATING FIBROUS MATERIAL.

Application filed October 17, 1922. Serial No. 595,174.

To all whom it may concern:

Be it known that I, HOWARD M. DUDLEY, a citizen of the United States, and a resident of Philadelphia, Pennsylvania, have invented certain new and useful Improvements in Apparatus for Dyeing or Otherwise Treating Fibrous Material, of which the following is a specification.

My invention relates to apparatus employed for dyeing goods or material in the mass; that is to say, finished goods such as hosiery or the like, which may be loosely disposed in a drum containing the dyeing or treating liquid. Apparatus of this type is particularly applicable for dyeing hosiery in bulk, although available for dyeing or otherwise treating other forms of material under similar conditions.

One important object of my present invention is to provide an imperforate, rotating drum, the interior of which comprises a continuous chamber, with foraminous compartments or hollow partitions extending longitudinally of and projecting a short distance into the space of said chamber radially; certain of said compartments lying adjacent to the outer imperforate wall of the drum casing, while other compartments lie adjacent to a central shell or partition.

A further object of my invention is to provide means for circulating the dyeing or treating liquid in two directions through the interior of the chamber provided by the rotatable drum.

A further object of my invention is to provide means for introducing steam into the chamber of the drum, and a still further object of my invention is to provide means whereby the drum and its contents may be rotated while the means through which the dyeing or treating liquid is introduced and discharged and the means employed for introducing a heating medium such as steam or any other fluid, remain at rest.

These and other features of my invention are more fully described hereinafter; reference being had to the accompanying drawings, in which:

Figure 1, is a longitudinal elevation of one form of apparatus within the scope of my present invention, in section on the line I—I, Fig. 3.

Fig. 2, is a longitudinal sectional elevation of the rotatable drum, on the line II—II, Fig. 3.

Fig. 3, is a cross sectional view on the

line III—III, Fig. 1, showing the drum in the closed and operative condition.

Fig. 4, is a similar cross sectional view showing the door of the drum chamber open to discharge the contained material.

Fig. 5, is a sectional view on the line V—V, Figs. 1 and 2, looking in the direction of the arrow a.

Fig. 6, is a sectional view on the same line, looking in the direction of the arrow b.

Fig. 7, is a perspective view of the foraminous compartments or hollow partitions disposed within the chamber of the rotatable drum.

Figs. 8 and 9, are enlarged sectional views of said foraminous compartments.

Fig. 10, is a similar sectional view of a modified construction within the scope of my invention.

Fig. 11, is a view in elevation of the structure in Fig. 10.

Fig. 12, is an enlarged sectional view of a portion of the structure illustrated in Fig. 1, and

Figs. 13 and 14, are sectional views on the lines XIII—XIII, and XIV—XIV, Fig. 12, looking in the direction of the arrows x and y, respectively.

The rotatable drum forming the subject of my present invention may be made up of an end wall 1, an annular wall 2, and an end wall 3; the latter carrying a plurality of hollow, foraminous compartments or hollow partitions, 4 and 4^a, disposed on one side of the same and projecting into the chamber 5 of the drum, and a series of tubular channels 6 and 6^a, disposed on the opposite side of said wall 3, for the passage of dyeing or treating liquid to and from the drum, as more fully described hereinafter. The solid portions of the end wall 3, together with the end wall 1, and the annular wall 2, form an internal chamber 5, for the reception of the material to be treated, through which chamber the treating or dyeing liquid may be circulated via the foraminous compartments 4 and 4^a, and the tubular channels 6 and 6^a.

The annular wall 2 of the drum may be provided with a door 7, closing a discharge outlet 8, and such door may be connected to the wall 2, by hinges 9. This door may have its marginal edges grooved at 10, for the reception of a gasket 10^a, for contact with the outer surface of the annular wall of the drum, and clamping means may be provided whereby said door is held in liquid-

tight engagement with said annular wall. Said clamping means may comprise L-shaped members 11, adapted to overlie the door and fit over bolts 12, carried by the 5 annular wall 2; being held down by nuts 12^a, provided with suitable operating handles. If desired, this door 7 may carry a supplemental door 7^a, held thereto in liquid-tight engagement in the same manner that the 10 door 7 is held to the annular wall of the drum; such door 7^a being hinged to the door 7 at 9^a, and closing an opening 8^a, through which samples of the material under treatment may be removed from time to time to 15 observe the action of the dyeing or treating liquid thereon.

As indicated above, the interior of the drum is continuous so that the material under treatment is free to move throughout 20 the same; being tumbled about in contact with the dyeing or treating liquid as the drum rotates. In order that this action may beneficially affect the material during a dyeing or treating operation, I extend into the 25 drum from the wall 3, and in the present instance constituting a part of said wall 3, a series of foraminous compartments, hollow partitions or liquid conveying channels 4 and 4^a; those indicated at 4 lying adjacent 30 to and being supported by the annular wall 3, while those indicated at 4^a lie adjacent to and may be supported by the walls of a central core or partition 13, as clearly shown in 35 the drawings. On the opposite side of said wall 3, the series of hollow channels 6 and 6^a are provided, through which the dyeing or treating liquid may be passed from a suitable source to and from the drum chamber 5; the channels 6 communicating with 40 the compartments or hollow partitions 4, and the channels 6^a communicating with the compartments or hollow partitions 4^a, respectively.

The foraminous compartments or liquid 45 conveying channels 4, lying adjacent to the annular wall 2, may have a cross sectional contour such as illustrated in Figs. 5, 6 and 7, and the interior of the same may be divided into a plurality of chambers, two in 50 the present instance, indicated at 14 and 15, separated by a foraminous wall 16. The wall of the chamber 14 may be rounded as indicated and perforated or otherwise apertured as indicated at 17, and this chamber 55 serves as a portion of the liquid conduit; that is to say, the liquid may enter the drum chamber through the apertures 17 leading from the chamber 14 of the compartments 4, or it may be discharged from the drum 60 chamber through these apertures.

The foraminous compartments or liquid 65 conveying channels 4^a lying adjacent to the walls of the central core or partition 13, have a cross sectional contour substantially like that of the compartments 4, and the inte-

rior of the same may be divided into a plurality of chambers, two in the present instance, indicated at 14^a and 15^a, separated by a foraminous wall 16^a. The wall of the chamber 14^a may be rounded as indicated, 70 and perforated or otherwise apertured as indicated at 17^a, and serves as a portion of the liquid conduit, that is to say, the liquid may enter the drum chamber 5 through the apertures 17^a leading from the chamber 14^a of 75 the compartment 4^a, or it may be discharged from the drum chamber through these apertures.

The chambers 15 and 15^a contain pipes 18 and 18^a, a portion of the wall of which is 80 perforated at 19 and 19^a adjacent the foraminous partition walls 16 and 16^a, so that steam or other fluid passed into said pipes 18 and 18^a from a suitable source may be discharged therefrom through the apertures 19 and 19^a, thence through the foraminous walls 16 and 16^a, into the chambers 14 and 14^a, and out through the apertures 17 and 17^a of the latter, together with the treating or dyeing liquid, into the drum chamber 5. 90 The foraminous compartments or hollow partitions 4 and 4^a may be flanged as indicated at 20 and 20^a; the flanges 20 lying adjacent the outer wall to the drum, while the flanges 20^a of the compartments 4^a serve 95 as supports for the wall of the central core or partition 13.

The channels 6 and 6^a carried by the wall 3 may extend diagonally toward a shell-like structure comprising a pair of chambers concentrically disposed; the channels 6 communicating with an outer chamber indicated at 100 25, while the channels 6^a communicate with an inner chamber indicated at 26. The walls of these chambers may be bell-mouthed as indicated at 25^a and 26^a to receive the projecting ends of a hollow liquid-conveying structure which may have an outer wall 28 and an inner wall 29 concentric with said 110 outer wall; the bell-mouth 25^a of the outer chamber 25 additionally receiving packing material 30, which may be held in place by a gland 31, suitably arranged to take up such packing and insure a liquid-tight joint between said bell-mouth and the wall 115 28. The inner wall 29 may fit within the bell-mouth of the inner chamber 26, the meeting faces of the walls of the respective members being such as to permit rotation of one with respect to the other. Although the 120 annular walls 28 and 29 are shown as fitting within the bell-mouths 25^a and 26^a, it will be understood that the relation of parts may be reversed without departing from my invention. The arrangement indicated is more 125 convenient. To insure a liquid seal between the contacting surfaces of the bell-mouth 26^a and the wall 29, these surfaces may be annularly grooved as indicated at 33 and 34 respectively; such grooves preferably regis- 130

tering and being adapted to receive any liquid which may seep between the surfaces, and such liquid collecting in such registering grooves will prevent passage of the flowing liquid past the joint so formed.

The annular chambers formed by the walls 28 and 29 are merged into upper and lower passages 28^a and 29^a, each having a cross partition 28^b and 29^b; which passages may be placed alternately in communication with passages 35 and 36; the latter having a cross partition 36^a, communicating with both sides of a suitable pumping structure indicated at 37, which may be driven by any suitable means; a pulley 38, being shown, receiving a belt 39 actuated by a suitable prime mover (not shown). A pipe for delivering dyeing or treating liquid, or water to the pump is shown at 40, and a tank 41 for containing any treating material may communicate with a conduit 36^a between the passage 36 and the pump via a valved outlet 42.

The relation of the passages 28^a, 29^a and 35 and 36 may be controlled by a gate valve 45 having a stem 46, passing through a suitably packed gland 47, and connected to an operating lever or handle 48 so that the liquid can be directed as desired; that is to say, such liquid can be delivered from the passage 35, to the passage 28^a, thence to the chamber 26 and channels 6^a, and discharged from the foraminous compartments 4^a into the drum chamber 5, and returned through the foraminous compartments 4 and channels 6 to the chamber 25, passage 29^a and passage 36 to the pump, as indicated in Fig. 1; or discharged through the foraminous compartments 4 and return through the foraminous compartment 4^a and the respective passages, without changing the direction of the movement of the pump. Provision is made for introducing any desired chemical into the dyeing or treating liquid; the tank or receptacle for such purpose being indicated at 41, and the pipe 40 supplying dyeing or treating liquid or water may be provided with a valve 40^a.

At the opposite end of the drum, the end plate 1 may be provided with a thickened hub 49 receiving a steam or fluid conveying pipe 50 with a suitable packed joint; a gland 51 being provided for the purpose, and such end wall may be bored to provide a series of channels 52 and 53 for the passage of steam or other fluid. The inner ends of these channels communicate with the pipes 18 and 18^a disposed within the chambers 15 and 15^a of the respective foraminous compartment elements 4 and 4^a; such pipes having a portion of their walls perforated throughout their length so that the steam or other fluid may be discharged therefrom and find its way through the foraminous partitions 16 and 16^a into the chambers 14 and 14^a of said foraminous compartments to heat

or otherwise affect the body of dyeing or treating liquid passing through the same, as hereinbefore described.

The hub member 49 may carry a cone 55, between which and a second cone 56, carried by a support 57, anti-friction balls, 58 may be placed, to provide a suitable bearing. The shell at the opposite end of the drum providing the chambers 25 and 26, may also be provided with a cone 55^a, between which and an outer cone 56^a, carried by a support 57^a, anti-friction balls 58^a may be disposed.

By providing the angularly disposed channels 6 or the shell forming the chambers 25 and 26 with a suitable pulley face, such as indicated at 60, in Fig. 1, the drum may be rotated by means of suitable belt from a driven element, or, in lieu of the pulley face, such shell may carry a gear wheel 61, to be positively driven by a motor driven pinion, or from any other suitable form of prime mover, as shown in Fig. 2.

The drum may be provided with a drain valve 62, disposed near the marginal wall thereof, and the end wall 1, may carry one, or a series of liquid gage glasses 63, in order that the height of the dyeing or treating liquid in the drum may be ascertained at any time.

While I have shown in Figs. 1, 2, 3, et seq., foraminous compartments or hollow partitions 4 and 4^a, disposed within the drum chamber and comprising apertured shells carried by or attached to the end plate 3 and extending longitudinally of the drum chamber, it is possible to modify such construction without departing from my invention, and to employ a construction such as illustrated in Figs. 9, and 10, in which a channel member 65 may be provided and arranged to receive a pipe 18^b apertured for the discharge of steam or other fluid, and in lieu of a chamber 14 or 14^a, having an apertured wall through which the dyeing or treating liquid passes, this wall may be made up of a series of longitudinal rods or bars 66 forming a slatted construction through which the liquid may be discharged into the drum chamber or from which it may be withdrawn, depending upon the direction of movement of the same.

While I have shown and described an end plate 3 as carrying the foraminous compartments 4 and 4^a on one side, and the channels 6 and 6^a, on the opposite side, and as integral parts of said plate 3, it will be understood, of course, that these several members may be separately constructed and properly secured to said end plate 3 in order that the proper conduits or passages for the liquid will be provided so that such liquid may pass into two directions to and from the drum chamber 5, without departing from my invention. If desired, the end wall construc-

tion may include a casing in the form of a truncated cone, as indicated by dotted lines, Figs. 1 and 2, and this casing may be integral with or independent of the several channels, 5 as may be convenient or desirable.

While I have described my improved apparatus as being specially designed for dyeing, preferably for dyeing material in bulk, it will be understood that it may be employed for various materials and for the purpose of scouring and bleaching, and that in lieu of introducing dye liquor into the drum chamber receiving the material operated upon, I may introduce gaseous bodies, 15 bleaching fluids, scouring liquids or the like, without departing from my invention.

I claim:

1. In apparatus for dyeing or otherwise treating fibrous material, the combination of 20 a rotatable shell forming a liquid containing drum, a series of foraminous compartments projecting into said drum and extending longitudinally thereof out of contact with each other; the inner space of the drum chamber being otherwise clear and permitting free movement of the goods under treatment, and means for circulating treating liquid continuously through said compartments and drum chamber.
2. In apparatus for dyeing or otherwise treating fibrous material, the combination of 25 a rotatable shell forming a liquid-containing drum, a series of foraminous walled compartments extending longitudinally of said drum, each of said compartments having a plurality of chambers and said compartments being disposed out of contact with each other whereby the interior of the drum is relatively clear, and means for passing 30 treating fluid through the chambers of said compartments for delivery into said drum.
3. In apparatus for dyeing or otherwise treating fibrous material, the combination of 35 a rotatable drum, two sets of foraminous compartments extending longitudinally of said drum; one set being disposed adjacent to the peripheral wall of the drum and the other set being disposed adjacent to the central portion of the drum and the inner space 40 of the latter being otherwise clear, and means for introducing treating fluid into said drum through one set of said compartments and discharging it from said drum through the other set of compartments.
4. In apparatus for dyeing or otherwise 45 treating fibrous material, the combination of an imperforate rotatable shell forming a liquid-receiving drum, a series of foraminous compartments extending longitudinally of said drum, the inner space of the same being otherwise clear, hollow trunnions at 50 opposite ends of said shell in communication with said compartments and adapted to receive fluid for delivery thereto, and means 55 for introducing different bodies of treating

fluid through said trunnions and into said compartments.

5. In apparatus for dyeing or otherwise treating fibrous material, the combination of 70 an imperforate rotatable shell forming a liquid-receiving drum, a series of compartments having foraminous walls extending longitudinally of said drum, the inner space of the latter being otherwise clear; each of said compartments having a plurality of 75 chambers, hollow trunnions at opposite ends of said drum communicating with said compartments and adapted to receive fluid, means for introducing treating fluid through one of said trunnions and into one of the 80 chambers of each of said compartments, and means for introducing steam through the other trunnion and into one of the chambers of each of said compartments.

6. In apparatus for dyeing or otherwise 85 treating fibrous material, the combination of a cylindrical shell forming an imperforate drum, a series of foraminous compartments extending longitudinally of said drum and set radially with respect to the 90 same; the interior of the drum being otherwise clear for the reception and free movement of the material within the same, means for rotating the drum, and means for circulating liquid through said foraminous 95 compartments in both directions.

7. In apparatus for dyeing or otherwise 100 treating fibrous material, the combination of a cylindrical shell forming an imperforate drum, a series of foraminous compartments extending longitudinally of said drum and set radially with respect to the same, the interior of the drum being otherwise free for the reception and movement of the material within the same, means for rotating the drum, channels externally disposed communicating with said compartments, and means for delivering liquid to 105 said channels for circulation through said foraminous compartments in both directions.

8. In apparatus for dyeing or otherwise 110 treating fibrous material, the combination of an imperforate cylindrical shell, means for rotating the same, two sets of foraminous compartments extending longitudinally of said drum and disposed radially with respect to the same; one set being disposed adjacent the peripheral wall of the drum and the other set being disposed centrally of the drum and the interior of the latter being otherwise free for the reception and movement of the material within the same, and means for circulating treating liquid through said foraminous compartments in both directions.

9. In apparatus for dyeing or otherwise 115 treating fibrous material, the combination of an imperforate cylindrical shell forming a drum, a plate closing one end of said drum, foraminous compartments carried on one 120

5 side of said plate and projecting into the drum, and fluid receiving channels carried at the opposite side of said plate and communicating with said foraminous compartments.

10. In apparatus for dyeing or otherwise treating fibrous material, the combination of an imperforate cylindrical shell forming a drum, a plate closing one end of said drum, two sets of foraminous compartments carried on one side of said plate and projecting into the drum, two sets of fluid receiving channels carried at the opposite side of said plate and communicating with said foraminous compartments, manifolds for said sets of channels, and means for delivering liquid to one of said sets of channels.

15. In apparatus for dyeing or otherwise treating fibrous material, the combination of an imperforate cylindrical shell forming a drum, means for rotating the same, a plate closing one end of said drum, two sets of foraminous compartments carried on one side of said plate and projecting into the drum; one set being disposed peripherally and the other set centrally of said drum, two sets of fluid receiving channels carried at the opposite side of said plate and communicating with said foraminous compartments, and means for delivering fluid to either set of channels.

20. In apparatus for dyeing or otherwise treating fibrous material, the combination of an imperforate cylindrical shell forming a drum, means for rotating the drum, foraminous compartments extending longitudinally of said drum the inner space of the latter being otherwise clear; channels communicating with said compartments, a trunnion having concentrically arranged passages in communication with said channels, means for pumping through certain of said channels in one direction and through other channels in another direction while the drum is rotating, and a valve for controlling the direction of fluid moving through the respective channel.

25. In apparatus for dyeing or otherwise treating fibrous material, the combination of an imperforate cylindrical shell forming a drum, means for rotating the drum, two sets of foraminous compartments extending longitudinally of said drum the inner space of the latter being otherwise clear; two sets of channels communicating with the respective sets of compartments, a trunnion having concentrically arranged passages in communication with said channels, and means for introducing fluid into said drum through one set of said channels.

30. In apparatus for dyeing or otherwise treating fibrous material, the combination of an imperforate cylindrical shell forming a drum; said drum having an opening, a cover hinged to said drum and closing said opening, means for rotating the drum, fo-

35 raminous compartments extending longitudinally of said drum and each having a plurality of chambers the interior of the drum being otherwise free for movement of the material and treating liquid within the 70 same; channels communicating with one of the chambers of said compartments, means for delivering fluid to said channels for passage through one of the chambers of said compartments, pipes in the other chambers 75 of said compartments, and means for delivering a different fluid body thereto for passage to the drum.

40. In apparatus for dyeing or otherwise treating fibrous material, the combination of an imperforate cylindrical shell, means for rotating the same, two sets of foraminous compartments extending longitudinally of said drum and disposed radially with respect to the same; one set being disposed adjacent to the peripheral wall of the drum and the other set being disposed adjacent to the central portion of the drum and the interior of the latter being otherwise free for the reception and movement of the material 80 within the same; each of said foraminous compartments having a plurality of chambers, means for circulating treating liquid through one of the chambers of said foraminous compartments in both directions, and 85 means for introducing a fluid through the other chamber of said compartments for 90 passage to the drum chamber.

45. In apparatus for dyeing or otherwise treating fibrous material, the combination of a rotatable shell forming a liquid-containing drum, means for rotating said drum, a series of foraminous compartments extending longitudinally of said drum out of contact with each other; the inner 100 space of the drum chamber being otherwise clear, and means for circulating treating fluid continuously through said compartments and drum chamber during 105 rotative movement of the structure. 110

50. In apparatus for dyeing or otherwise treating fibrous material, the combination of a rotatable shell forming a liquid-containing drum and adapted to receive material to be treated, means for rotating said drum, a plurality of sets of foraminous compartments extending longitudinally of said drum out of contact with each other; the inner space of the drum chamber being otherwise clear, and means for circulating treating fluid continuously through said compartments and drum chamber during the 115 rotative movement of the structure. 120

55. The combination of a rotatable shell forming a liquid-containing drum and adapted to receive material to be treated, means for rotating said drum, a series of foraminous-walled compartments extending longitudinally of said drum; each of said compartments having a plurality of cham- 125 130

bers and said compartments being disposed out of contact with each other whereby the interior of the drum is relatively clear, and means for circulating treating fluid through 5 the chambers of said compartments and the drum during the rotative movement of the structure.

19. The combination of a rotatable shell forming a liquid-containing drum and 10 adapted to receive material to be treated, means for rotating said drum, a plurality of sets of foraminous-walled compartments extending longitudinally of said drum; each 15 of said compartments having a plurality of chambers and said sets of compartments being disposed out of contact with each other whereby the interior of the drum is relatively clear, and means for circulating treating fluid through the chambers of said com-

partments and the drum during the rotative movement of the structure. 20

20. In apparatus for dyeing or otherwise treating fibrous material, the combination of a cylindrical shell forming an imperforate drum, a series of foraminous compartments set radially with respect to and projecting into said drum and extending longitudinally thereof; the interior of the drum being otherwise clear for the reception and free movement of the material undergoing treatment within the same, means for rotating the drum, and means for delivering liquid for circulation through said longitudinal foraminous compartments and into the chamber of the drum in both directions. 25 30

In witness whereof I have signed this specification.

HOWARD M. DUDLEY.
